UNITED STATES PATENT OFFICE

1,959,051

COVER MOUNTING FOR RECEPTACLES

John F. Geibel, Buffalo, N. Y., assignor to Master Metal Products, Inc., Buffalo, N. Y., a corporation of New York

Application May 18, 1932, Serial No. 612,046

2 Claims. (Cl. 4-290)

This invention relates generally to receptacles but more particularly to a cover mounting for waste receptacles, sink strainers and the like.

The chief object of the invention is to provide simple and inexpensive means for pivotally connecting the cover to the receptacle whereby the cover is reliably held against transverse displacement relative to the receptacle.

In the accompanying drawing:—Figure 1 is a perspective view of a sink strainer showing my invention applied thereto. Figure 2 is an enlarged side elevation thereof, partly in section, and showing the cover in its inverted position beneath the strainer bottom. Figure 3 is a fragmentary rear view of the strainer partly in section, showing the pivotal connection of the cover. Figure 4 is a fragmentary perspective view showing a slightly modified form of the invention.

Similar characters of reference indicate corresponding parts throughout the several views.

By way of example, the invention has been shown in connection with a receptacle in the form of a sink strainer consisting of a container or receiver 10 for the garbage or refuse which may be stamped from sheet metal or like material and of any suitable shape. Its bottom 11 may be perforated as seen at 12 and its rear wall and the corresponding upper edge are preferably straight, except at the corners, which may be curved or rounded. The upper edge of the container may be provided with a bead or curl 13 which serves to strengthen it and render its open end smooth. As seen in Figures 1 and 3, this bead extends around the front and sides of the container and preferably terminates at a point where the rear rounded corners of the container blend into its substantially straight rear wall.

Applied to the container to assume a position over its open end or below its strainer bottom, is a closure or cover 14 which is hingedly connected to the rear wall of the container to swing vertically relatively thereto. The preferred means for so hinging the cover to permit it to assume either of the positions stated consists of a bail or loop 15 of wire which is shaped approximately into the form of a U, the free ends 16 thereof being pivotally connected to the marginal rim or flange 17 of the cover in the manner shown in Figure 1. The intermediate or cross-bar portion 18 of the bail is fulcrumed at the upper edge of the rear wall of the container 10 preferably through the medium of companion hinge elements or loops 19 which may be formed integrally therewith. As seen in Figures 1 and 3, these hinge loops are spaced transversely of the rear wall

of the container on opposite sides of the longitudinal center thereof, and coextensive with this space such rear wall has a notch or recess 20 which extends a suitable distance below the hinge axis of the bail.

For the purpose of preventing lateral displacement of the cover 14 and its bail 15 relative to the container 10, and thereby always insure the proper positioning of the cover over or beneath the container, I preferably provide the hinge portion 18 of the bail with stop means which cooperate with the companion hinge loops. As shown in Figures 1 and 3 of the drawing, the stop means preferably consists of a bend or offset 21 formed in that portion of the bar 18 which extends across or spans the gap between the hinge loops. This offset or bend provides oppositely facing stop shoulders 22 which are adapted to abut against the opposing edges of the hinge loops 19 and thereby prevent displacement of the bail 75 relative to the container.

If desired, the bend or offset for preventing relative displacement of the bail and its cover may be formed or shaped in the manner shown in Figure 4, thereby providing a loop or hanger eye 23 which may be employed for supporting the receptacle or hanging it upon a wall when not in use.

I claim as my invention:—

1. A garbage receptacle having a strainer bottom and laterally-spaced hinge loops formed at its upper edge, a closure member having a bail pivotally connected to said hinge loops and adapted to swing vertically to assume a position over the receptacle or beneath its strainer bottom, said bail extending across the space between the hinge loops and being offset from its pivotal axis to form stop shoulders engageable with the opposing ends of said hinge loops.

2. A cover mounting for receptacles, comprising a substantially U-shaped bail having its free ends terminating in pivot elements engageable with the opposite sides of the cover, the cross bar of said bail being hingedly engageable with the receptacle and having a loop-like element formed thereon intermediate its ends forming a combined stop for axial movement of the bail relative to the receptacle and a handle for suspension of the receptacle.

JOHN F. GEIBEL. 105

CERTIFICATE OF CORRECTION.

Patent No. 1,959,051.

May 15, 1934.

JOHN F. GEIBEL.

It is hereby certified that error appears in the printed specification of the above numbered patent requiring correction as follows: Line 102, claim 2, before "axial" insert limiting; and that the said Letters Patent should be read with this correction therein that the same may conform to the record of the case in the Patent Office.

Signed and sealed this 19th day of June, A. D. 1934.

Bryan M. Battey
